KARL AUERBACH, OF SAALFELD-ON-THE-SAALE, GERMANY, ASSIGNOR TO HERMAN F. HOEVEL, OF NEW YORK, N. Y.

MACHINE FOR UPSETTING AND LIKE OPERATIONS

Application filed July 14, 1926, Serial No. 122,347, and in Germany July 17, 1925.

My invention relates to machines for performing operations such as upsetting, by means of a reciprocating member or plunger. It is applicable particularly to machines for upsetting the ends of rods or bars, as well as for upsetting intermediate portions of a blank, so as to produce thereon an enlargement or collar. The object of my invention is to provide an arrangement which enables 5 the plunger, or the slide carrying such plunger, to be stopped, after each operation, at various points of its stroke or travel, under the operator's selective control. The plunger slide, with this arrangement, will be returned 10 automatically after the upsetting operation and, when or after passing the dead center, will come to a stop automatically at such a distance from the backing or abutment engaged by the blank, that after removal of 15 the upset blank the machine will be ready for the next operation immediately, without requiring any manipulation on the part of the attendant. All the operator has to do, is to start the machine and to insert and remove 20 blanks during the stoppage of the machine. In view of the automatic operation of the machine, the attendant may, while the machine is in motion, get the next piece or blank ready for insertion into the machine, thus 25 speeding up the operation and not only increasing the output of the machine, but also diminishing the liability of objectionable cooling of previously heated blanks while they are waiting to be inserted into the machine.

The invention comprises a special stop device, adjustable circumferentially of a rotary member which controls the operation of the upsetting slide; said stop co-operating 40 with a clutch-shifting mechanism to bring about the stoppage of the machine, the exact time of such stoppage being determined, at the operator's selection, according as the said stop is adjusted to different positions circumferentially of said rotary controlling member. When the end of the blank is to be upset, it is generally preferable to let the plunger slide continue its return movement for 45 some time after the end of the upsetting operation; when however intermediate portions

of the blank are to be upset, it is desirable, as a rule, to arrest the machine when the plunger has just completed its upsetting operation, that is to say, when the eccentric employed in machines of this character is in 55 its dead center position.

Two satisfactory examples of my present invention will now be described in detail with reference to the accompanying drawings, in which Fig. 1 is a side elevation illustrating one from of my invention, and Fig. 2 is an end elevation thereof, with parts in section; Fig. 3 is a side elevation showing another embodiment of my invention, and Fig. 4 is an end elevation of such second embodiment.

At 10 I have indicated the body or frame of the machine, provided with longitudinal tracks or guideways 11 for the reciprocating slide 12 carrying the plunger 13, which may 15 be of any customary or approved construction and operates to upset the blank against a suitable backing or abutment 14, likewise of any customary or approved construction. The slide 12 is operated by means of a rod 16 from an eccentric 16 on a shaft 17, this general type being well-known in the art. The shaft 17 is journaled in a bearing 18 on the body or frame 10, and also in another bearing provided in a standard 19. On said shaft 20 is mounted loosely so that it may rotate thereon, yet held against longitudinal motion, a pulley 20 adapted to be rotated continuously by a driving belt 21, said pulley having a clutch member adapted to be engaged by a 25 companion clutch member 22 likewise mounted loosely on the shaft 17 and adapted not only to rotate thereon but to slide lengthwise thereof, into and out of engagement with the clutch formation on the driving pulley 20. The clutch member 22 is splined or otherwise connected with a pinion 23 mounted loosely on the shaft 17, in such a manner that the parts 22 and 23 are compelled to rotate in unison, but the pinion 23 will be held against movement lengthwise of the shaft 17, the member 22 sliding lengthwise relatively to said pinion as the clutch is being thrown in or out. The pinion meshes with a spur gear 24 30 integral or rigid with a pinion 25 meshing 35

with a spur gear 26 mounted rigidly on the shaft 17, said wheels 24 and 25 rotating about an axis parallel to said shaft.

On the gear wheel 26 is provided an actuating plug 27 whose function is to throw out the clutch and thus stop the shaft 17 and the plunger 13 at the desired moment. This lug is adapted to come in contact with a companion lug 28 on the clutch lever 29, fulcrumed at 30 and having the well-known 10 forked end engaging the clutch member 22 at a groove, or any other suitable connection for shifting the clutch member 22 lengthwise of the shaft 17. The lever 29 has a pin-and-slot connection 31 with a foot lever 32 fulcrumed at 33 and provided with a treadle 34. The connections are so arranged that depression of the treadle will shift the member 22 into engagement with the pulley 20 and thus start the machine, while the lug 27, when it comes 20 against the lug 28 during the rotation of the shaft 17, will shift the member 22 out of contact with the driving pulley 20 and thus stop the machine, this movement of the lug 28 also bringing the treadle 34 back to its upper position. It will be understood that the lugs 27, 25 28 have surfaces beveled in the proper direction to effect the operation described above.

The actuating lug 27, which thus forms 30 part of a device for stopping the shaft 17, may be adjusted to different positions circumferentially of the gear wheel 26. For this purpose I may provide said wheel with a plurality of surfaces or seats 35 to fit the corresponding surface of the lug 27 which in this case is secured detachably to any one of said seats 35, at the operator's selection, in any suitable manner, for instance by means of screws 36 passing through said lugs and fitted 40 into threaded openings 37.

By shifting the lug 27 circumferentially of the wheel 26, I may stop the shaft 17 selectively at different points of the travel or stroke of the plunger 13. Thus, I may 45 arrange to have such plunger stop automatically at or near the dead center, that is, practically coincident with the moment that the upsetting operation is completed. This, as stated hereinbefore, is the preferred way 50 when the upset portion of the blank is an intermediate portion thereof. When, however, the end of the blank is to be upset, the actuating lug 27 will generally be set in such a way, that the machine will not be stopped until 55 the plunger has gone a material distance beyond the dead center position of the eccentric 16.

Instead of making the actuating lug detachable for the purpose of adjusting it to 60 different circumferential positions, I may provide a construction in which the said lug will remain permanently on the rotary member carrying it, but will still be adjustable circumferentially thereof. An instance of 65 such a construction is shown in Figs. 3 and

4. Here the actuating lug 27' is mounted, not on the gear wheel 26, but on a disk 38 which is normally held rigid with the shaft 17, as by set screws 39, so that said disk and actuating lug will rotate with the shaft. By 70 loosening the set screws, the disk 38 is freed for circumferential adjustment, so that the actuating lug 27' may be brought to any desired position circumferentially, with respect to the position of the eccentric 16. The result 75 will be, of course, a change in the timing of the stop mechanism of which said lug forms a part. In the specific construction illustrated by Figs. 3 and 4, the lug 27' is adapted to engage the beveled end of a lever 40 fulcrumed on the body or frame 10 at 41, thus swinging said lever and, through the medium of a link 42 and a crank arm 43 held to turn with the foot lever 32', operating said foot lever in such a direction as to raise the treadle 34 and shift the clutch member 22 into the 80 released position to stop the shaft 17.

The operation, in either of the examples illustrated, will be as follows: The actuating lug 27 or 27' is set to the proper position, 90 as required by the particular work to be done, circumferentially on the rotary member carrying such lug, with respect to the position of the eccentric 16. The blank, having been heated in any well-known or approved 95 manner, is placed in the die or backing 14, and the treadle 34 is depressed. This will start the machine, and the operator is relieved of further attention until the machine is stopped automatically by the action of the 100 lug 27 or 27' on the parts co-operating therewith. The operator is thus free to devote his time to heating or otherwise preparing the next blank, and the output of the machine is thus increased, besides insuring a better and 105 more uniform quality of the work as there is no loss of time during which the blank might cool off to a point impairing the efficiency of the operation.

Various modifications may be made without departing from the nature of my invention as set forth in the appended claims.

I claim:

1. In a machine for upsetting and like operations, a rotary member, blank-working 115 mechanism operated by said member and including an abutment and a plunger movable relatively thereto, a device for stopping the rotation of said member, and an actuator for said stop device, said actuator being held to 120 rotate with said rotary member and adjustable to different positions circumferentially of said rotary member to vary the stoppage of said plunger relatively to said abutment.

2. In a machine for upsetting and like 125 operations, a shaft, an eccentric thereon, blank-working mechanism operated by said eccentric and including an abutment and a plunger movable relatively thereto, a device for stopping the rotation of said shaft, and 130

an actuator for said stop device, held to rotate with said shaft and adjustable circumferentially to different positions relatively to the position of said eccentric, to vary the stoppage of said plunger relatively to said abutment.

- 5 3. In a machine for upsetting and like operations, a rotary power transmitting member, blank working mechanism operated by
10 said member, a device for stopping the rotation of said member, a disk arranged to rotate with said power transmitting member and adapted to be rotatively adjusted relatively thereto, and an actuator for said stop
15 device fixed upon said disk and adjustable thereby about the axis of rotation of said power transmitting member to different fixed positions to vary the timing of the stoppage of such member.
20 In testimony whereof I have hereunto set my hand.

KARL AUERBACH.
